CLAIM

The ornamental design for a light-emitting device having two light-emitting areas, as shown and described.

DESCRIPTION

FIG. 1 is a first perspective view of a light-emitting device having two light-emitting areas showing our new design; FIG. 2 is a second perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; and, FIG. 8 is a bottom plan view thereof.

(Continued)

The broken lines illustrate portions of the portions of the light-emitting device having two light-emitting areas, which form no part of the claimed design.

1 Claim, 6 Drawing Sheets
